UNITED STATES PATENT OFFICE.

FRANK J. HINDERLITER, OF TULSA, OKLAHOMA.

ECCENTRIC GRAB.

Application filed November 7, 1925. Serial No. 67,484.

This invention relates to fishing tools for recovering lost articles in the bottom of drill holes as in the oil well drilling industry.

Many varieties of articles are dropped down unprotected drill holes from time to time, as well as other fragments resulting from broken drills, rotary bits with pins broken off, underreamers and the like. If the lost article is of sufficient size to stand nearly upright in the drill hole, it is ordinarily a simple matter to fish it out. On the other hand, smaller articles may fall over in the hole and if casing is used the extremities thereof may lie outside the clear diameter of the casing so that the article may have to be tilted or righted before it can be gripped and hoisted through the casing. In the description that follows, a broken underreamer cutter has been chosen for specific illustrative purposes only. The present invention has for its object providing means for righting or shifting an article lost in a drill hole and means for gripping the same after righting.

Other and further important objects of this invention will be apparent from the disclosures in the specification and the accompanying drawings.

This invention (in a preferred form) is illustrated in the drawings and hereinafter more fully described.

On the drawings:

Figure 1 is a front elevation of a device embodying the features of this invention;

Fig. 2 is a section on the line II-II of Figure 1 showing the device lowered through a casing in position to pick up an article lost in the hole;

Fig. 3 is a section similar to Figure 2 showing the action of the spud in straightening the lost article into a position where it can be picked up;

Fig. 4 is a similar section showing the device gripping the lost article;

Fig. 5 is a section on the line V-V of Figure 1; and

Fig. 6 is a section on the line VI-VI of Figure 1.

As shown on the drawings:

A line of casing is indicated by the numeral 10, a shoe 11 being shown on the bottom thereof in the drill hole 12. It is customary under certain circumstances to use such casing around the drill bit and closely following the same, so that the bit necessarily takes the form of an expansion or

underreamer in order to be lowered through the casing. The underreamer cutters such as shown at 13 in the drawings are comparatively delicate and occasionally break off and drop to the bottom of the hole preventing further drilling. Also when the drilling tools are hoisted out a miscellaneous assortment of hand tools are likely to be dropped down the casing and it is frequently a considerable task to fish such lost articles out of wells, as the lost articles usually lie in such a position that they must be aligned with the hole before they can be gripped and hoisted through the casing. In order to accomplish this result the body or shank 14 of the gripping tool, having the usual pin 15 for attachment to the rods, is provided with an eccentric or off-set semicircular spud 16, the offset of the spud being preferably the maximum that will go down the casing. This spud serves to strike and force one end of the lost article downwardly thus tipping the other end up, as shown in Figure 3, into a position to be engaged by the gripping mechanism.

If the lost article is substantially circular the spud may be provided with a pair of slips 17 which slide in inclined grooves 18 and are provided with gripping teeth which are forced into the article to be lifted by the weight thereof acting in conjunction with the wedging action of the inclined grooves. The slips are held from dropping out by a tongue and groove construction in the grooves together with pins 19 below the slips.

The main gripping mechanism or grab comprises a pivoted lever 20 mounted in a recess 21 in the shank of the tool, the pivot being located at 22. The upper end of the lever 20 is undercut to receive the ends of a pair of coil springs 23 positioned in suitable wells in the shank, and the lower end of the lever ends short of the point of the spud in a serrated surface 24 having an outwardly beveled smooth point 25 adapted to slide over the outer and upper corner of a lost tool to assist the spud in righting the same. When the tool is to be lowered down a drill hole the grab is expanded in any suitable manner and a breakable pin 26 inserted between the serrations 24 on the lever 20 and a recess 27 provided in the wall of the spud. This pin is intended to be knocked out of the way or broken by the tool being driven down over the top of the lost article as shown in Figures 3 and 4. It is not necessary that

2
the pin be either fragile or ductile for the reason that it can be forced out even if unyielding, but a fragile pin offers less resistance to the top of the lost article so that it is preferable.

In the use of this recovery tool the lever or grab 20 is first propped in extended or open position by the pin 26 and is lowered in the casing. When the eccentric spud 10 clears the bottom of the casing it swings over to the side of the drill hole as shown in the figures, the projecting pointed end of the spud engaging one corner of the lost article and straightening or righting the 15 same by driving down on the string of tools, thus placing the article in a position so that it will pass up into the grab and be gripped thereby after displacing the pin 26.

I am aware that many changes may be 20 made, and numerous details of construction may be varied through a wide range without departing from the principles of this invention, and I therefore do not purpose limiting the patent granted hereon, otherwise than necessitated by the prior art.

I claim as my invention:

1. In a tool of the class described, a recessed shank, a gripping lever pivoted in said recessed shank, springs associated with

said lever, a serrated surface on the projecting end of said lever forming a grab, a prop for holding the projecting end of the lever distended, and a semicircular spud extending below and opposite to said grab and adapted to right an object lying at the bottom of the drill hole. 30

2. In a tool of the class described, a recessed shank, a gripping lever pivoted in said recessed shank, springs associated with 40 said lever, a serrated surface on the projecting end of said lever forming a grab, a prop for holding the projecting end of the lever distended, and a semicircular spud eccentrically disposed with respect to the shank 45 extending below and opposite to said grab and adapted to right an object lying at the bottom of the drill hole.

3. In a recovery tool a shank, a spud on 50 said shank and offset with respect thereto, a serrated gripping lever pivoted to said shank and disposed opposite to said spud, said gripping lever being shorter than said spud and serrated slips associated with said spud in opposed relationship with the serrated surface of said lever. 55

In testimony whereof I have hereunto subscribed my name.

FRANK J. HINDERLITER.
